UNITED STATES PATENT OFFICE

140,507

DESIGN FOR A COMBINATION MANTELPIECE AND BAR OR SIMILAR ARTICLE

Stephen Kuchta, Bronx, N. Y., assignor to V. P.
Michael J. Le Pane, Jamaica, N. Y.

Application January 5, 1945, Serial No. 117,279

Term of patent 14 years

(Cl. D13—5)

To all whom it may concern:

Be it known that I, Stephen Kuchta, a citizen of the United States, and residing in the Borough of Bronx, county of Bronx, city and State of New York, have invented a new, original, and ornamental Design for a Combination Mantelpiece and Bar or Similar Article, of which the following is a specification, reference being had to the accompanying drawings, forming part thereof.

Fig. 1 is a front elevational view of a combination mantelpiece and bar showing my new design;

Fig. 2 is a top plan view of Fig. 1;

Fig. 3 is a side elevational view of Fig. 1 with the parts thereof in closed position;

Fig. 4 is a view similar to Fig. 3, but with the parts thereof in open position;

Fig. 5 is a view similar to Fig. 1, but with the parts in open position;

Fig. 6 is a perspective view of the combination mantelpiece and bar with the parts thereof in open position.

I claim:

The ornamental design for a combination mantelpiece and bar or similar article, as shown.

STEPHEN KUCHTA.
